UNITED STATES PATENT OFFICE.

CARL E. TANNEWITZ, OF GRAND RAPIDS, MICHIGAN.

INK-WELL.

1,178,553.

Specification of Letters Patent. Patented Apr. 11, 1916.

Application filed August 2, 1915. Serial No. 43,235.

To all whom it may concern:

Be it known that I, CARL E. TANNEWITZ, a citizen of the United States, residing at Grand Rapids, Michigan, have invented 5 certain new and useful Improvements in Ink-Wells, of which the following is a specification.

This invention relates to improvements in ink wells.

10 The main objects of this invention are: First, to provide an ink well of the type comprising a holder and a removable ink receptacle with an improved cover. Second, to provide in an ink well of the type described an improved cover which effectively 15 closes the ink receptacle even though it be arranged in the holder in an inclined or tilted position or even though its top be inclined. Third, to provide in an inkwell an 20 improved cover provided with a receptacle closure of non-corrodible waterproof material by which the cover is effectively protected from the ink evaporation by such receptacle closure.

25 Further objects, and objects relating to structural details, will definitely appear from the detailed description to follow.

I accomplish the objects of my invention by the devices and means described in the 30 following specification.

The invention is clearly defined and pointed out in the claims.

A structure which is a preferred embodiment of my invention is clearly illustrated 35 in the accompanying drawing, forming a part of this specification, in which:

Figure I is a plan view of an ink well embodying the features of my invention. Fig. II is a detail vertical section on a line corresponding to line 2—2 of Fig. I. Fig. III is a detail vertical section on a line corresponding to line 3—3 of Fig. I. Fig. IV is a horizontal section on a line corresponding to line 4—4 of Fig. III. Fig. V is a detail 40 vertical section showing the cover slightly raised and illustrating the adjustability of the closure. Fig. VI is a detail section similar to that of Fig. III, through the holder and receptacle showing the adjustability of the cover to a receptacle in an inclined position. Fig. VII is a detail vertical section through the holder and receptacle, similar to that of Fig. II, further showing the adjustability of the ink receptacle closure 45 to a receptacle in an inclined position.

In the drawings similar reference char-

acters refer to similar parts throughout the several views, and the sectional views are taken looking in the direction of the little arrows at the ends of the section lines. 60

Referring to the drawings, 1 represents a support, such as the top of a desk or the like, having a hole 2 therein for the holder barrel 3. This holder barrel is formed of sheet metal rolled into cylindrical form and is provided with a rim 4 at its upper edge adapted to rest on the surface of the support in a suitable countersink therein, if preferred. The edges of the barrel are slightly separated at 5 so that the barrel may be 65 sprung into the opening and expanding therein grip the opening for retaining the holder. Toothlike lugs 6 are struck out from the barrel to assist in retaining it in the support. The barrel is provided with rests 7 for the ink receptacle 8. These rests 7 are struck in from the holder barrel which is also provided with lateral receptacle supports 9 and 10. The rests 7 are arranged so that the upper edge of the receptacle is a 80 substantial distance below the rim 4. The cover 11 is hinged to the rim at 12. The cover has a portion 13 rearwardly of its hinges so that by pressure thereon the cover is raised. The rim is also notched at 14 to 85 facilitate the opening of the cover. The cover hinges are arranged so that the cover closes into the rim and is flush with the top thereof. A disk-like closure member 15 preferably of moisture-proof and non-corrodible material is provided for the ink receptacle 8. The material commonly known to the trade as vulcanized cotton fiber and the grades or brands known by the trade names of "Bakelite" and "Condensite" are 90 found to be satisfactory for these closures. This closure is loosely mounted on the headed studs 16 depending from the cover, the studs being arranged through holes 17 in the closure and the holes being of such 95 size as to allow vertical and tilting adjustment of the closure. With the parts thus arranged the closure is opened with the cover and swings out of the way when the cover is open. When the cover is closed this 100 closure rests upon and adjusts itself to the top of the receptacle and is supported so as to adjust itself to the top of the receptacle although the receptacle may be in a tilted position or the top be in an inclined position. This insures an effective closure for the ink receptacle preventing undue evaporation of the 105 110

ink and protecting it from dust and it also prevents the moisture of evaporation reaching the cover and corroding the same.

I have illustrated and described my improvements as I have adapted and embodied the same in ink wells adapted to be inserted in desk tops. Certain features are readily adaptable and desirable for use in other forms of ink wells. I have not illustrated or described such modifications or embodiments as I believe the disclosure made will enable those skilled in the art to which my invention relates to embody or adapt the same as may be desired.

Having thus described my invention, what I claim as new and desire to secure by Letters Patent, is:

1. In an ink well, the combination of an ink receptacle, a holder therefor comprising a barrel having inwardly projecting receptacle supporting lugs, a rim for said barrel, a cover hinged to said rim and adapted to close into the same, a moisture-proof and non-corrodible closure disk for said ink receptacle, and stud-like headed supports on which said closure disk is loosely mounted depending from said cover.
2. In an ink well, the combination of an ink receptacle, a holder therefor comprising a barrel having inwardly projecting receptacle supporting lugs, a rim for said barrel, a cover hinged to said rim and adapted to close into the same, and a moisture-proof non-corrodible closure disk for said ink receptacle loosely mounted on said cover for vertical and tilting movement whereby it is adapted to adjust itself to and rest upon the

top of the ink receptacle when said cover is closed.

3. In an ink well, the combination of an ink receptacle, a holder therefor, a cover hinged to said holder, a closure disk for said ink receptacle, and stud-like supports on which said closure disk is loosely mounted depending from said cover. 45

4. In an ink well, the combination of an ink receptacle, a holder therefor, a cover hinged to said holder, and a moisture-proof non-corrodible closure disk for said ink receptacle loosely mounted on said cover for vertical and tilting movement whereby it is adapted to adjust itself to and rest upon the top of the ink receptacle when said cover is closed. 50

5. In an ink well, the combination of an ink receptacle, a holder therefor, a cover hinged to said holder, and a closure for said ink receptacle loosely mounted on said cover for vertical and tilting movement whereby it is adapted to adjust itself to the ink receptacle when said cover is closed. 60

6. In an ink well, the combination of an ink receptacle, a holder therefor, a cover hinged to said holder, and a closure for said ink receptacle adjustably mounted on said cover so that it may adjust itself to the ink receptacle when said cover is closed. 65

In witness whereof, I have hereunto set my hand and seal in the presence of two witnesses.

CARL E. TANNEWITZ. [L. S.]
